JAMES G. HAYMAKER, OF SALEM CROSS-ROADS, PENNSYLVANIA.

Letters Patent No. 69,429, dated October 1, 1867.

IMPROVEMENT IN HORSE-COLLARS.

The Schedule referred to in these Letters Patent and making part of the same.

TO ALL WHOM IT MAY CONCERN:

Be it known that I, JAMES G. HAYMAKER, of Salem Cross-Roads, in the county of Westmoreland, and State of Pennsylvania, have invented a new and useful Improvement in Horse-Collars; and I do hereby declare that the following is a full, clear, and exact description thereof, which will enable others skilled in the art to make and use the same, reference being had to the accompanying drawing, forming part of this specification.

This invention relates to an improvement in horse-collars, and consists in a novel construction and arrangement of a lock inside and upon the lower part of the collar, which is divided at the bottom, whereby the collar can be placed on the horse without passing it over his head.

The accompanying drawing is a perspective view of part of my improved collar, with a perspective section showing the lock-spring in place.

A A is the lower part of the body of the collar, B a catch, and C an entering piece, both firmly set in or cast in one piece, with the smooth-surfaced plate D made to fit neatly inside the bottom of the collar, the leather being secured round it. B' C' are openings in the opposite part of the body of the collar to receive B and C, the spring b' having a lip at its extremity securing the catch B. A smooth-surfaced plate D' fitting in the collar, and having the leather securely fastened round it, holds the spring in place. The upright a' is pivoted to the spring b, and is arranged in the collar so as not to interfere with the tongue-strap. By pressing on the thumb-piece a the catch B is released from the spring b, and the collar may be then opened. The thumb-piece a may be countersunk in the collar. A second catch may be substituted for the pin or entering piece C, with an appropriate spring for the hole C', or a second pin may be substituted for the catch B of spring b', according to the strength required in the collar.

What I claim as new, and desire to secure by Letters Patent, is—

1. The catch B, secured to plate D on one end of the collar, and spring b' in the opposite end, with or without the pin or entering piece C and hole C', applied to the lower portions of a divided horse-collar, and locking them together, substantially as described.
2. The pin or entering piece C and hole C', with or without the catch B and spring b', applied in like manner and for like purpose, substantially as described.

JAMES G. HAYMAKER.
